TIE HOLDER

Carl A. Anderson, Cranston, R. I., assignor to Anson Incorporated

Application January 13, 1948, Serial No. 143,692

Term of patent 7 years

(Cl. D17—10)

To all whom it may concern:

Be it known that I, Carl A. Anderson, a citizen of the United States, residing at Cranston, in the county of Providence and State of Rhode Island, have invented a new, original, and ornamental Design for a Tie Holder, of which the following is a specification, reference being had to the accompanying drawing, forming a part hereof.

Fig. 1 is a front elevation of a tie holder, showing my new design; and

Fig. 2 is a side view thereof.

I claim:

The ornamental design for a tie holder, substantially as shown.

CARL A. ANDERSON.
